BY

Geo. B. Willard

ATTORNEY

UNITED STATES PATENT OFFICE.

THOMAS B. MONOSMITH, OF BAY CITY, MICHIGAN.

LAMP-HOLDER.

981,586.

Specification of Letters Patent. Patented Jan. 10, 1911.

Application filed June 1, 1909. Serial No. 499,451.

To all whom it may concern:

Be it known that I, THOMAS B. MONOSMITH, a citizen of the United States, residing at Bay City, in the county of Bay and State of Michigan, have invented certain new and useful Improvements in Lamp-Holders; and I do hereby declare the following to be a full, clear, and exact description of the invention, such as will enable others skilled in the art to which it appertains to make and use the same.

My invention relates to lamp holders and more particularly to that class of lamp holders designed to receive an electric search light employed for exploring purposes.

My invention is adapted for use in many lines, such as in repairing machinery where it is necessary to crawl under or through normally moving parts where it is impracticable to suspend the ordinary electric light; also in vaults, closets and the like where a continuously burning light is not necessary.

The invention is also adapted for use on motor vehicles when it is necessary to inspect and repair the mechanism.

One object of my invention is to provide a device of this nature wherein the strain is taken up by the holder and cord, to avoid the imposition of excessive strain upon the lamp socket in the holder.

Another object of my invention is to provide a holder which does not necessitate the soldering of the reflector to the holder.

Another object of my invention is the provision of novel means for firmly connecting the cord to the holder without injury to the cord.

Another object is the provision of means for preventing the twisting of the connecting cord.

A still further means is the provision of a neat, simple article of this description, which is easily taken apart for inspection and adjustment, and which may be readily reassembled.

To these and other ends, my invention consists in certain novel features and combinations such as will be more fully described hereinafter and particularly pointed out in the claims.

In the accompanying drawings, Figure 1 is a perspective view of my invention, Fig. 2 is a longitudinal sectional view, Fig. 3 is a detail perspective view of the clamping jaws disassembled, Fig. 4 is an end view showing the nipple with its ribs, and Fig. 5 is

a detail cross-sectional view on line $\alpha-\alpha$ of Fig. 2, and Fig. 6 is an enlarged longitudinal sectional view of the clamping device.

Heretofore lamp holders for exploring purposes have been so arranged that the strain caused by the operator in poking the lamp into dark corners, has been sustained by the lamp socket to which the circuit wires are soldered. The objection to this is that frequently the socket is damaged, the wires pulling out of the socket and considerable expense incurred in repairing the construction.

It is my endeavor to provide a practical, simple lamp holder which is inexpensive and will fulfil every requirement.

Referring to the drawings, A indicates the lamp holder which may be made of any suitable material as gutta-percha, for instance, and of any suitable shape. In the present instance I have shown such holder as being of the usual bell shape, the apex of such holder having affixed thereto a hollow nipple 1, the free end of which is exteriorly threaded. The hollow nipple communicates with the interior of the holder, the bore of the nipple being preferably provided with a plurality of ribs 2, 2, upon the inner ends of which is supported the end of the lamp socket 3. The nipple may be formed independently of and attached to the bell. In order to remove the strain caused in the use of this lamp holder, from the lamp socket 3, I provide the co-acting clamping members 4, 4. These co-acting clamping members are provided with convex tapering outer faces and flat inner faces. One of the clamping members 4 is provided with a recess 5 in its flat inner face, the opposing flat face of the other clamping member being provided with a ridge 6 extending transversely of the flat face and located opposite the recess 5 when the clamping members are in adjusted position.

Each of the clamping members terminates at one end in a tenon 7, which tenons are receivable in the sockets formed between the ribs 2, 2, in the nipple to prevent the rotation of the clamping members and one or both of the inner flat faces of the clamping members may be grooved as at 8, to receive the cord 9 leading from the lamp socket 3 to any suitable source of power. In order to retain the clamping members tightly clamped upon the cord 9 to prevent the

strain from being transmitted by the cord to the lamp socket, I provide the sleeve 10 having a tapered bore, one end of which is inferiorly threaded and adapted to be received upon the threaded end of the nipple 1. By screwing such sleeve down upon the nipple, the reduced portion of the bore of the sleeve is brought into engagement with the convex faces of the clamping members to squeeze them snugly together upon the cord 9 and thereby prevent any strains from being transmitted to the lamp socket.

By providing the clamping members with the tenons 7 received in the sockets formed between the ribs 2, I prevent the clamping members from being rotated as the sleeve is screwed into position and thus avoid twisting the cord which would result in injuring its connection with the lamp socket. The tenons 7 may be of less length than the ribs 2 and one or both of the tenons may be grooved in alinement with the groove or grooves on the inner faces of the clamping members to form a seat for the cord 9.

5. Any suitable reflector (not shown) may be secured within the bell which is provided with an annular groove 11, to receive a retainer of any suitable description, not shown, and removable therewith, or such reflector may be otherwise secured within the flaring end of the holder.

The lamp is easily removed when burned out and the nipple and sleeve serve as a handle which is grasped by the operator, such handle being virtually solid and hence strong and rigid.

The inner end of the lamp socket is snugly seated on the inner ends of the ribs to prevent its vibration in the holder, being held in its seat by the tension on the cord. Such tension is not increased during the use of the lamp, however, owing to the clamping means which maintains the cord stretched between the lamp socket and the jaws. It is obvious that the cord might be twisted in removing and replacing the lamp 12, to prevent which I preferably groove the inner periphery of the nipple as at 13, to receive a key 14, such key being usually formed by the solder by which one wire of the cord is connected to the socket 3. This maintains the socket against rotation when the lamp is being removed and replaced. I may also interpose a gasket or washer 15 between the inner end of the lamp socket and its apertured seat to absorb shocks or jars and prevent undue strain from being placed on the connections of the lamp cord therewith. Thus, by means of the clamping jaws and the key and key seat, I have reinforced and strengthened the weakest points of former exploring lamps.

I prefer in some cases to equip the handle portion of my lamp holder (which in this instance consists of the enlarged lamp re-

ceptacle A, the tube 1, and the sleeve 10, the tube and sleeve serving as a handle) with a flange 16 which in effect, permits the structure to be used as a hand rest on which to wind the cord 9. The flange prevents the cord wound on the handle from slipping off and tangling. A notch 17 is formed in the periphery of the flange to receive the cord which is wound on the handle, the free end of the cord being inserted through an aperture 18 which prevents the cord from unwinding. The notch prevents the cord from slipping around the flange.

From the foregoing it is evident that I have devised a most simple and inexpensive lamp holder for the purposes set forth and one which is easily assembled and disassembled for repairs or inspection, and it is obvious that changes might be made in the form and arrangement of the several parts described without departing from the spirit and scope of my invention.

Having thus fully disclosed my invention, what I claim as new, is:

1. A lamp holder comprising a lamp-receiving receptacle, a tubular member connected therewith and adapted to receive a lamp socket and cord, clamping members between which the cord is received, the inner face of one of the clamping members being recessed, the inner abutting face of the remaining clamping member having a ridge extending thereacross opposite the recess in the first-named clamping member, the inner face of at least one of the clamping members being grooved to receive the lamp cord, and means removably connected to the tubular member and surrounding the clamping members to retain them snugly upon the cord.

2. A lamp holder comprising a lamp-receiving receptacle, a tubular member connected therewith and adapted to receive a lamp socket and cord, clamping members between which the cord is received, the clamping members provided with tenons receivable in sockets formed in the tubular member, the lamp cord received between the clamping members, and means removably receivable on the tubular member and encircling the clamping members to clamp them upon the cord.

3. A lamp holder comprising a lamp-receiving receptacle, a tubular member connected therewith and adapted to receive a lamp socket and cord, clamping members between which the cord is received, a recessed seat formed in the tubular member for the lamp socket, tenons on the clamping members receivable in the seat, and means removably receivable on the tubular member and encircling the clamping members to snugly clamp them together on the lamp cord.

4. A lamp holder comprising a lamp-re-

ceiving receptacle, a tubular member communicating therewith, ribs in the tubular member, the member adapted to receive a lamp socket seated on the inner ends of the ribs, 5 clamping members, one end of each of which is received in the tubular member and held against rotation, the clamping members adapted to receive the lamp cord between their abutting faces, and means removably receivable on the tubular member and encircling the clamping members to snugly clamp them together on the lamp cord.

5. In combination with a lamp, cord, and lamp holder, a threaded nipple secured to 5 the lamp holder, a plurality of ribs in the

bore of said nipple, a threaded sleeve formed with a tapered bore, a plurality of tapered clamping members received in said sleeve, tenons formed on the ends of said clamping members and adapted to engage the 20 ribs of said nipple to prevent rotation of said members when the sleeve and nipple are screwed together.

In testimony whereof, I affix my signature in presence of two witnesses.

THOMAS B. MONOSMITII.
